UNITED STATES PATENT OFFICE.

CARL H. SCHMIDGALL, OF PEORIA, ILLINOIS.

BORING TOOL.

Application filed April 15, 1927. Serial No. 184,029.

This invention relates to boring tools particularly of that type for boring holes of irregular form.

An object of the invention is to provide a tool of a particularly rugged structure capable of performing heavy continuous work in practically all forms of material including metal.

Another object is to provide a boring tool wherein all strains are relieved from the gear members employed for driving the cutters with which the tool is provided to the end that said tool will have long life and continue to bore accurately.

Still another object is that of employing milling cutters as part of the boring elements of a form adapted to operate in conjunction, certain of them intermeshing with and timed with the main cutters for removing any slight material left by said main cutters.

Other objects and advantages will be made known herein aided by the appended drawing wherein

Figure 1 is an elevation of the boring tool as seen in one of its positions.

Figure 2 is an elevation of a portion of the same rotated one quarter turn from the position shown in Figure 1.

Figure 3 shows the tool as seen from its boring end.

Figure 4 is a transverse section of the tool on line 4—4, Figure 1, and

Figure 5 illustrates a part of the tool as seen in Figure 2, but greatly enlarged, being in part section to show interior construction, and with the cutter seen Figure 2 removed.

I am familiar with the art pertaining to boring tools of the type mentioned and shall point out wherein the tool under consideration differs in structure and advantages.

The handle of the tool is denoted by the character 1, which is of generous proportions but reduced at one end into a spread flattened body 2. Substantially central of the body and extending from each of its opposite flat faces is a raised integral flange 3. Inward from the flanges, which coincide in position on the body, are four holes 4 cutting entirely through the body 2. These holes are spaced equal distances apart and are all spaced equally from a central point within the confines of the said flanges 3. Having position within each hole is a bevel pinion 5 two of which lie opposite one an-

other with their axes in line with the longitudinal line of the tool while the other two, likewise opposite each other, lie with their axes at right angles to the first two 60 described. One of the pinions is mounted on a drive shaft 6 extending through the handle 1, said shaft being reduced in diameter inward from the pinion and has a bearing in a socket 7 of the body. The pinion 65 lying opposite that carried by said shaft 6 is mounted on a shaft 8 which has a bearing in the outer end of the body 2 and likewise seated in a socket 9. Said shaft extends out through the end of the body and has a 70 shoulder at 10 to bear against the end of the body, a cutter 11 being mounted on said shaft.

The other remaining pinions 5 are carried each on a shaft 12 journaled in the body 2 75 and projects through the edges of the same, being each provided with a cutter 13. The inner end of the shafts, as in the other instance, rest in sockets 14 and it is now seen that each of the shafts considered herein 80 has a bearing in the body 2 at opposite sides of the pinion carried by it.

The pinions all have the same number of teeth and these project from the holes 4 in which they are positioned, all being adapted 85 to mesh with two gears 15, one at each side of the body, said gears being part of or affixed to cutters 16, Figure 4.

A hub or boss 17 extends from each side of the body centrally of the flange 3 and each receives one of the cutters 16. A threaded hole 18 extends through both bosses and a screw 19, but one of which is shown, Figure 4, serves to maintain the gears 15 and pinions in operative engagement. Each cutter 16 has an annular groove 20 in its inner face adapted to receive into it the adjacent flange 3 when the gears are brought into mesh with the pinions, said cutter thus constituting means for excluding dust and cuttings from the working parts within. The cutters 16 are patterned after a well known type of milling cutter, being relieved at each side, as shown, leaving the teeth thereof projecting to provide 100 for a clearance way for said cutter, or rather its body. The type of tooth is clearly indicated in Figures 1, 2 and 3.

The cutters 13 are of the star type and are greater in diameter than the distance 110 between the teeth of the cutters 16 and lie in such a position as to work through the

teeth of the latter. That is to say, the pinions 5 have ten teeth, the gears 15 have twenty, there being therefore a two to one ratio. The cutters have five teeth and the 5 teeth of the cutters 16 are twenty in number. It will be understood, therefore, that although the diameter of the cutters is greater than the distance between the teeth of cutters 16 as stated, the teeth of the two 10 sets of cutters by their proper timing will intermesh after the fashion of meshing gear teeth except that there need be no contact thereof. The purpose of this action is that material that is not removed by the cutters 15 16 where it lies between them will be entirely removed by the intermeshing of both sets of teeth leaving a clean smooth hole. A study of Figure 3 will show that a clean square hole would be bored.

20 Power applied to the shaft 6, through the pinion thereon, will drive the other three pinions in the same direction since all of them are engaged by both gears 15. The two cutters 16 will therefore rotate in opposite directions, their teeth being oppositely directed for that reason. In boring wood, the cutter 11 may be used but for metal work the tool is used without this member, the body 2 being entered into a previously 25 prepared hole, milling the metal away to create a square aperture or apertures of other shapes depending upon the forms of cutters employed.

30 Holes of larger diameter than can be bored with the size of tool illustrated herein may be created by substituting cutters corresponding to 16 but of greater diameter and thickness, the cutters 13 being replaced by those of greater thickness to the end that 35 the teeth of both sets of cutters will still provide clean walls in the bore. Also, cutters of different forms may be substituted for all those shown so that various holes of various shapes may be bored.

40 It is to be noted that there are no strains on any of the pinions other than the driving strains in that, first, the shaft 8 carrying the cutter 11 bears against the body 2 by its shoulder 10 and the pinion of that shaft, therefore, will not be crowded into the gears 15. Second, the drive shaft 6 is socketed at 7 so that pressure necessary for boring is placed against the body 2. Again, since each of the shafts is journaled at both 45 sides of the pinion it carries, there can be no lateral strains on them which would be particularly true of the shafts 12 carrying the cutters 13 where considerable lateral strain would be imposed by the latter. Further, the cutters 16 with their gears 15, it will be observed, are journaled on the studs or bosses 17 and the latter since integral with the body 2 and of generous diameter and proportion constitute a very rigid support for said cutters, the bearing thereon

being wide so that these members cannot rock and cramp their gears upon the pinions. The tool is thus very sturdy throughout, it can give no trouble, and is excellently fitted for long use under heavy duty. Also, in 70 addition to the facts pointed out the body 2 is a one-piece structure so that there can be no racking or weaving as would be possible when using a body of connected parts.

Referring again to the boring of metal 75 where a round hole has already been bored, a plug, not shown, that just fits said hole takes the place of the cutter 11 and guides the milling cutters to the work.

I claim:

1. A boring tool including a substantially flat body having a series of openings extending through it from side to side, said openings being disposed in even spaced relation, a pinion in each opening, a separate 85 shaft for each pinion, two of them being in line with the longitudinal axis of the body, and one of them extending out through said body at its narrow side acting as a drive shaft, two of the other shafts lying at right 90 angles to the axis of the drive shaft extending from the edges of the body, a cutter on the outer end of each, and a gear at each flat side of the body in mesh with the several pinions, each including a cutter. 95

2. A boring tool including a substantially flat body having a series of openings extending through it from side to side, said openings being disposed in even spaced relation, a pinion in each opening, a separate 100 shaft for each pinion, two of them being in line with the longitudinal axis of the body, and one of them extending out through said body at its narrow side acting as a drive shaft, the other also extending out through 105 said body at its opposite narrow side, a boring tool carried by the last named shaft, a shaft lying at right angles to the drive shaft in each side of the body and each extending out through the narrow side of the same, 110 a cutter on the outer end of each, and a gear at each flat side of the body in mesh with the several pinions, each including a cutter.

3. A boring tool including a one-piece body having a series of four openings extending entirely through it opening upon opposite sides of said body, the same being evenly spaced from one another around a common point and equi-distant from that point, a pinion in each opening, a separate 115 shaft for each pinion, all of said shafts lying in the same plane and extending out through the other sides of the body radiating from said common point, one of said shafts acting as a drive shaft, a cutter mounted on each 120 of two of the shafts that lie axially in line with one another and at right angles to said drive shaft, a fixed stud or boss extending from opposite sides of the body at right 125 angles to the plane in which the shafts lie, 130

5 a gear at each of two sides of the body meshing with all of the pinions, and a cutter fixed with respect to each gear, each combined gear and cutter being rotatable upon one of said studs or bosses.

10 4. A boring tool including a body of a single part having a series of four openings extending through it from one side to the other and being equi-distant from one another around a common point, a pinion in each opening, a separate shaft for each pinion, each shaft having a bearing at each side of the pinion carried by it, one of the shafts acting as a drive shaft, a cutter on each of 15 two of the shafts that lie at right angles to said drive shaft, a fixed stud or boss extending from opposite sides of the body at right angles to the plane in which the shafts lie, and a gear including a cutter mounted 20 to rotate on each stud or boss, each said gear meshing with all of the pinions.

25 5. A boring tool including a body having an annular flange extending from each of two opposite sides thereof, driving pinions within said body within the confines of the flanges, a gear journaled at each of two opposite sides of the body meshing with said pinions, and a cutter fixed with respect to each gear, each said cutter having an annular groove in its face to receive into it a 30 flange of said body.

35 6. A boring tool including a body having an annular flange extending from each of two opposite sides of the same, gearing in said body, a cutter mounted to rotate at each of two opposite sides of the body driven by said gearing, each cutter having an annular groove in one of its faces coinciding in position with the flanges and adapted to 40 receive one of the same into it.

45 7. A boring tool including a body, driving gearing therein, a toothed cutter at each of two opposite sides of the body rotatable in planes paralleling one another, a toothed cutter at each of two other sides of the body rotatable in planes at right angles to the direction of rotation of the first described cutters and lying between the latter, all of the cutters being driven by said gearing, the teeth of corresponding cutters being timed in their movement to intermesh with those of the other pair.

55 8. A boring tool including an elongated body, a drive shaft extending longitudinally through the same and having a driving pinion thereon, a gear at each of two opposite sides of the body meshing with said pinion, each including a toothed cutter, a toothed cutter at each of two other sides of the body

whose teeth are adapted to intermesh with those of the first named cutters, and a pinion operatively connected with each of the second named cutters for driving the same and each meshing with the gears of said first named cutters.

60 9. A boring tool including an elongated body, a drive shaft extending longitudinally through the same and having a driving pinion thereon, a gear at each of two opposite sides of the body meshing with said pinion, each including a toothed cutter, a toothed cutter at each of two other sides of the body whose teeth are adapted to intermesh with those of the first named cutters, a pinion operatively connected with each of the second named cutters for driving the same and each meshing with the gears of said first named cutters, a shaft axially in line with the drive shaft including a pinion in mesh with the said gears, and a cutter mounted on 75 said shaft.

70 10. A boring tool including a body provided with a recess in its side and having a circular flange projecting from the surface of said side encircling the recess, a cutter having in one side a circular groove adapted to receive the flange into it, and also having gear teeth on said side extending into the recess, a driving pinion in said body extending into the recess engaging the teeth 80 of said cutter, and a bearing for said cutter.

75 11. A boring tool including a body provided with a recess in each of two opposite sides and having a circular flange extending from each side surrounding the recess therein, a hub extending from the bottom of each recess centrally with respect to the flange, a cutter bored to receive the hub and having a circular groove in one side to engage over the flange and also having teeth on that side 95 to lie in the recess, and a driving pinion within the body engaging the teeth of both cutters.

100 12. A boring tool including an elongated body, a driving shaft extending longitudinally through the same, a pinion thereon within the body, a cutter mounted at each of two opposite sides of the body including gear teeth to engage the pinion, a cutter mounted at each of two other sides of the body, and a pinion for driving each of the last named cutters, the same meshing with the gear teeth of the first named cutters, the teeth of one pair of the cutters arranged to intermesh with those of the other pair.

115 In testimony whereof I affix my signature.

CARL H. SCHMIDGALL.
